Fig. 4.

The diagram shows a rectangular frame structure. The top horizontal bar is labeled 17. The left vertical bar is labeled 13. The right vertical bar is labeled 14. The bottom horizontal bar is labeled 11. A curved line labeled 12 connects the top of the left vertical bar to the bottom of the right vertical bar. A curved line labeled 15 connects the top of the left vertical bar to the bottom of the bottom horizontal bar. A curved line labeled 16 connects the bottom of the right vertical bar to the bottom of the bottom horizontal bar. A small circle is located at the intersection of the top horizontal bar and the left vertical bar.

UNITED STATES PATENT OFFICE

OTTAVIO CHIOCCHIO, OF PORT CHESTER, RYE, NEW YORK

RUNNING MOLD

Application filed July 24, 1930. Serial No. 470,498.

This invention relates to a tool or implement such as is primarily designed for use by plasterers and it has more particular reference to that species generally referred to in the prior art as a running mold, the same being intended for shaping, molding and various kinds of plastic bodies in the building trade.

As a general rule, running molds are of a make-shift construction; that is, they are individually made by the plasterers on the job for performing the task at hand. Unless the plasterer is a fairly skilled mechanic, these types of molds are ordinarily of a mediocre type, and consume much time and skill in the making thereof only to be discarded later.

The purpose of the present invention is to provide a permanent type of tool of a diversified form, characterized by a multiplicity of details mechanically allied into a new organization such as will fulfill the requirements of a tool of this kind in a highly satisfactory and economical manner.

The various elements embodied in this new composite tool will become more readily apparent from the following description and drawings. In the drawings:

Figure 1 is a side elevational view showing the complete details constituting the tool assembled for performing a certain character of work to be hereinafter described.

Figure 2 is an edge view of the structure seen in Figure 1, observing it in a direction from right to left.

Figure 3 is a top edge or plan view thereof.

Figure 4 is a perspective view of one of the attaching brackets.

Figure 5 is a perspective view of the right-angled form.

Figure 6 is a view showing the template mounted at right angles to the form for performing certain classes of work.

Figure 7 is a perspective view of the template per se.

Figure 8 is a top plan view of the structure represented in Figure 6.

Figure 9 is a perspective view of a matrix.

Figure 10 is a perspective view of an angle adjusting leg.

Referring first to Figure 1, attention is

called to the numeral 11 which designates the plate which may be structurally distinguished as a right angled form. A principle feature of this plate is the longitudinally extending shaping edge 12. As shown in Figure 5, this is provided with a plurality of distinguishable bolt holes 13, 14 15 and 16. This form is used when two flat walls meet at an angle greater than a right angle where it is desired to produce a rounded effect and the form may be used by itself.

It will be observed that along one edge is a laterally directed runner flange 17 designed to be placed on a rail or the like (not shown) to permit convenient operation in a conventional way. Secured by a pivot and retaining bolt 18 in the hole 15 is a blade or angle adjusting leg 19 which may be swung to the dotted out-of-the-way position shown in Figure 1 or which may be adjusted to various angles with respect to the shaping edge 12 to effect different angular shaping.

The part 11 in addition to serving as a form or tool in itself has the additional function of providing a mounting for a detail which is hereinafter designated as a template and indicated by the numeral 20. This template as shown in Figures 6 and 7 comprises a substantially plane plate having an approximately V-shaped notch 21 formed in one edge thereof.

At the apex or crotch portion of the notch is a bolt hole 22 to accommodate the matrix 23. The matrix is somewhat in the nature of a star wheel and is adjustably fastened in place by a screw, bolt, or the like 24 as shown in Figure 1. In this connection it will be observed that the matrix embodies a straight edge 25 and a series of distinguishable curvate edges 26, 27 and 28 respectively which may be adjusted to co-operate with the front portion of the notch 21 in a selective manner, according to the shape of the crown portion of the molding desired.

The opposite edge of the template is fashioned as at 29 to form what may be designated as an ornamental pattern which is useful when in the position represented in Figure 6. Adjacent this pattern are bolt holes 30 which match the aforesaid holes 13 and 14 to ac-

commodate fasteners 31 when in the position shown in Figure 1. Incidentally the configuration of the pattern 29 may be of variegated construction for different classes of work. In fact, any number of different types of templates may be supplied with the tool.

I now call attention to the numerals 32 which designate attaching brackets these having an attaching flange 33 secured to the form 10 plate 11 and having spaced parallel wings 34 apertured to permit the template to be secured therebetween in the relationship shown in Figure 6. The special template 20 is useful with or without the runner form 11, and 15 it may be attached thereto in the position shown in Figure 1 or in the right angular position shown in Figure 6. As a matter of fact, it is susceptible of use by itself.

Particularly do I wish to emphasize the 20 presence therein of the ornamental pattern 29 as well as the V-shaped notch 21 and the associated adjustable matrix 23 co-operating with the V-shaped notch.

I also wish to emphasize the individual- 25 ity of use of the form 11 as well as its use in combination with the template. Then too, I call attention to the presence therein of the attaching bracket 32 to permit the positioning of the template thereon. Moreover, I 30 expressly note the somewhat curvate shaping edge 12 and the co-operative angle adjusting legs 19 associated therewith. These details co-operate in such a manner as to render the structure usable in a wide range of plastic 35 formation.

It is thought that persons skilled in the art to which the invention relates will be able to obtain a clear understanding of the invention after considering the description in connection with the drawings. Therefore, a 40 more lengthy description is regarded as unnecessary.

Minor changes in shape, size, and rearrangement of details coming within the field 45 of invention claimed may be resorted to in actual practice if desired.

I claim:

1. As a new product of manufacture, a template comprising a substantially flat plate formed at one end portion with an approximately V-shaped notch, and formed in an adjacent edge portion with a pattern of a predetermined configuration, and a rotatable matrix superimposed upon the plate having 50 a plurality of differently shaped notches in its edge for selective co-operation with the crotch portion of said V-shaped notch.

2. As a new product of manufacture, a template comprising a substantially flat plate formed at one end portion with an approximately V-shaped notch, and formed in an adjacent edge portion with a pattern of a predetermined configuration, and an adjustable matrix superimposed upon the plate for co-operation with the crotch portion of said 55

V-shaped notch, and comprising a rotatable comparatively small plate having its marginal edge portions of distinguishable shapes any one of which is adapted to be brought into registration with the crotch of the V-shaped notch so as to permit the crown portion of the plastic formation acted upon by the notch of the template to be shaped in diversified manner.

3. A running mold for use by plasterers comprising a manipulating plate having a runner flange at one edge and another edge of arcuate shape for acting on the plaster, and a template adjustably and detachably attached to said plate, for selective projecting at different angles and from different edges of the template.

4. In a tool of the class described, a substantially flat plate formed along one longitudinal edge with a laterally projecting flange constituting a guide and runner, a pair of attaching brackets including spaced parallel companion portions detachably fastened to and extending at right angles from said plate at a predetermined point, and a template disposed between and detachably connected with said parallel portion and having one edge portion resting directly on said flange.

5. In a tool of the class described, a substantially right angle form in the nature of a substantially flat plate provided with a working and shaping edge of a predetermined obtuse angular formation, an angle adjusting leg pivotally mounted on the plate in a position to co-operate with said shaping edge when in a position projecting beyond said edge, said plate also having one edge formed with a flange constituting a guide and runner, a pair of attaching brackets including spaced parallel portions attached to and depending at right angles from said plate, and a template disposed between and detachably secured to said brackets and having one edge portion resting on said flange.

In testimony whereof I affix my signature.

OTTAVIO CHIOCCHIO.
